BLADE PACKAGE

Filed July 3, 1928

INVENTOR
H. J. Gaisman
BY
T. R. Bourne,
ATTORNEY

UNITED STATES PATENT OFFICE

HENRY J. GAISMAN, OF NEW YORK, N. Y., ASSIGNOR, BY MESNE ASSIGNMENTS, TO
GILLETTE SAFETY RAZOR COMPANY, OF BOSTON, MASSACHUSETTS, A CORPORATION
OF DELAWARE

BLADE PACKAGE

Application filed July 3, 1928. Serial No. 290,214.

An object of my invention is to provide a package of razor blades, in which the blades may be retained in a stack in a casing and may be discharged successively without requiring the blades to be handled until discharged.

Another object is to provide means for guiding the blades within the casing in such a way that the sharpened edges of the blades will be kept from contact with the casing, so as not to dull the blade edges while within or while being discharged from the casing.

A further object is to provide means for guiding the blades while being discharged in such a way that the sharpened edges of the blades will be kept from contact with the sides of the casing or its discharge opening by the action of the ejector.

In carrying out my invention I provide a casing adapted to retain a stack of blades therein, said casing having an outlet slot for delivery of the blades, an ejector slidably carried by the casing to engage the endmost blade of the stack to eject it, guiding means within the casing for the blades to keep their edges from engagement with the casing, and means to keep the blades snugged within the casing in position to be ejected successively.

My invention also comprises novel details of improvement that will be more fully hereinafter set forth and then pointed out in the claims.

Reference is to be had to the accompanying drawing forming part hereof, wherein

Fig. 1 is a perspective view of my improved blade package, illustrating the blade being discharged;

Fig. 2 is a sectional view substantially on the line 2, 2, in Fig. 4;

Fig. 3 is a sectional view on line 3, 3, in Fig. 2;

Fig. 4 is a cross section on line 4, 4 in Fig. 2;

Fig. 5 is a sectional plan view on line 5, 5, in Fig. 3;

Fig. 6 is a plan view of the blade illustrated in Figs. 1 to 5;

Fig. 7 is a partly sectional plan view on line 7, 7, in Fig. 8 illustrating a modification;

Fig. 8 is a cross section on line 8, 8, in Fig. 7;

Fig. 9 is a section on line 9, 9, in Fig. 7;

Fig. 10 is a perspective view of the blade package illustrated in Figs. 7 to 9, and

Fig. 11 is a plan view of the blade of Figs. 7 to 10.

Similar numerals of reference indicate corresponding parts in the several views.

The numeral 1 indicates a hollow casing adapted to contain a stack of razor blades 2. Said casing may be made of a single piece of metal drawn to shape and provided with an opening at one end to be closed by an end wall 3 that may be folded to closed position (Figs. 3 and 9) after the blades and other parts have been inserted within the casing.

A discharge opening or slot for the blades is indicated at 4, which may be provided by making the end wall 3 of suitable width so that when said wall is folded to place the opening or slot 4 will be provided. The marginal portions of the outermost blade of the stack are adapted to bear against the outer or top wall 5 of the casing, and the stack of blades is kept pressed toward said

wall by springs 6 which oppose the opposite or bottom wall 7 of the casing. The springs 6 are shown struck out from a metal plate 8 within the casing. In the form shown in Figs. 1 to 5 the plate 8 bears against the wall 7 and the springs bear against the adjacent blade of the stack, whereas in Figs. 7 to 10 the springs 6 bear against the wall 7 and the plate 8 bears against the adjacent blade of the stack, to keep the blades pressed toward

wall 5.

In Figs. 1 to 5 projections or posts 9 pass through openings 2a in all the blades except the endmost blade adjacent to the wall 5

to guide the blades and keep the edges from

- contact with the adjacent side walls of the casing. The projections 9 are shorter than the depth of the casing so that the outermost blade of the stack will be free from the 5 projections to slide through the outlet opening. The projections 9 are shown formed on the plate 8, which may be done by bending parts of said plate laterally from said plate. The projections 9 are shown so located as to engage the outer side walls 2' of the openings 2a of the blades, (Figs. 2 and 3), and since said walls are shown curved the guiding projections 9 are shown correspondingly curved.
- 10 In the form shown in Figs. 7 to 10, in which blades having single cutting edges are shown, the heels or back edges 2" of the blades engage the side wall 10 of casing 1, and the corners of the blades, at the ends 20 of the cutting edges, engage angularly disposed corners 11 of the casing, whereby the blades are guided with their cutting edges out of contact with the casing.
- 15 In order to permit the outermost blade of the stack to be ejected from casing 1, to avoid danger of the user's fingers engaging the cutting edges of the blade, I provide an ejector 12 that is slidable along the wall 5 against the outermost blade of the stack, which ejector is provided with a resilient projection 12a that is adapted to enter one of the openings 2a or 2b of the blade to push the latter through the discharge opening 4 of the casing. The ejector is shown slidably guided in a guiding recess or groove 13 (Figs. 4 and 8), which may be formed by pressing out the metal of wall 5 of the casing. Said pressed out portion of wall 5 is shown provided with a longitudinal slot 14 through 30 which a projecting finger-piece 12' extends from the ejector in position to be engaged by the user's finger to slide the ejector back and forth. When the ejector of Figs. 1 to 5 is moved to the right in Fig. 3 the outermost blade of the stack will be pushed through the discharge opening 4 of the casing in such a position as to be engaged by the fingers to pull the blade out of the casing, (Fig. 1), and the projections 9 will retain 45 the other blades of the stack from sliding. When the ejector has been pushed back (to the left hand side of Fig. 3) the springs 6 will push the stack of blades toward wall 5 for engagement of the ejector with the outermost blade, the latter being released from projections 9, and so on each time the ejector is slid back and forth. In the form shown in Figs. 7 to 10 the heels of the blades and their cutting-edge corners retain the blades of the 50 stack from displacement while the outermost blade is being ejected and while the ejector is pushed to the left in Fig. 9.
- 55 In the form shown in Figs. 1 to 6 the heel 12a of the ejector 12 operates on blade 2 by entering blade opening 2a and pushing

against the extreme ends of its wall 2c, thus keeping the outermost blade in alignment while being ejected, and also serving to retain the edges of the outermost blade, that is free from the projections 9, from engaging 70 the casing while said blade is retained in the casing, so that its cutting edges will not engage the casing. In the form shown in Figs. 7 to 11 the heel 12a of ejector 12 enters opening 2b of blade 2 (Fig. 11) and thus 75 keeps the alignment of the blade between said ejector heel, the heel 2" of the blade and the wall 10 of the casing, (Fig. 7 and 8), while said blade is being discharged so that its cutting edge will not engage the casing. 80

In accordance with my invention I provide a package of blades in which the blade edges are protected so as to avoid danger to the user's fingers in obtaining a blade from the casing, or in handling or transportation 85 of the package, and in which the blades need not be wrapped in paper or placed in envelopes separately, as has been the custom with safety razor blades. My improved blade package may be made cheaply so that the 90 casing may be discarded when all of the blades have been ejected therefrom.

Changes may be made in the details set forth without departing from the spirit of the appended claims. 95

Having now described my invention what I claim is:

1. A blade package comprising a casing having a blade outlet opening and having guiding means for a stack of blades to keep their cutting edges from contact with the casing while stacked therein, means to retain the blades pressed toward discharge position, and an ejector slidably carried by the casing and cooperative with an opening in the outermost blade to guide said blade in the longitudinal direction of its cutting edge and to discharge said blade with its cutting edge retained by said ejector out of contact with the casing while passing through said opening. 100

2. A blade package as set forth in claim 1 in which the blade guiding means is operative in openings in the blades except in the outermost blade. 105

3. A blade package comprising a hollow casing adapted to contain a stack of blades and provided with a blade outlet opening, means within the casing to retain the blades pressed toward discharge position, an ejector for the blades slidably guided by the casing and having a portion to enter openings in the blades to guide and eject the latter with their cutting edges out of contact with the casing, the casing having a longitudinal slot in one wall and the ejector having a projection extending through said slot for manipulation. 110

4. A blade package comprising a hollow casing having a guiding groove in one wall and a blade outlet opening, spaced blade 115

- guiding means within the casing spaced from side walls thereof to enter openings in a stack of blades to retain their edges out of contact with the casing, means to retain the 5 outermost blade of a stack of blades in discharge position respecting said opening, and an ejector guided in said groove and slidable relatively to the guiding means, said ejector having a portion to enter openings in the 10 blades to engage the latter to guide and eject the blades through said opening, said ejector having a finger piece in position to be manipulated, said wall of the casing being located on opposite sides of said groove in position for 15 the outermost blade to bear against said wall.
5. A blade package as set forth in claim 4 in which the said wall is provided with a longitudinal slot and the ejector finger piece extends through said slot in position to be 20 manipulated.
6. A blade package comprising a hollow casing having a blade outlet opening, a plate within the casing having springs to keep the blades pressed toward discharge position, said 25 casing being provided with spaced guiding projections adapted to enter correspondingly spaced openings in the blades to guide them to discharge position and keep their cutting edges out of contact with the casing, said 30 projections being shorter than the depth of the casing permitting the outermost blade to be free from the projections, and an ejector slidably carried by the casing to enter openings in the blades to guide them out of contact with the casing and to push the blades 35 through the outlet opening.
7. A casing for perforated razor blades, posts in the casing adapted to engage the blade perforations, an ejector on the casing 40 mounted to slide clear of the ends of the posts and adapted to eject the blades one at a time from the casing.
8. A casing for perforated razor blades, an ejector slidable in the casing, means urging 45 the blades into successive operative engagement with the ejector, means for operating the ejector to slide the blade engaged thereby out of the casing, and a pair of posts in the casing adapted to engage the perforations in 50 the blades remaining in the casing and serving to hold the edges of said blades out of contact with the casing.
9. A casing for perforated blades, means within the casing in position to engage the 55 blade perforations to hold the edges of blades out of contact with the casing, and an ejector slidable along the casing, said means being spaced from the ejector to permit the latter to slide clear of said means to eject the outermost blade through said space from the casing.
10. A casing for perforated blades, means within the casing in position to engage the blade perforations to hold the edges of blades 60 out of contact with the casing, and an ejector
- slidable along the casing, said means extending across the casing and being shorter than the distance from the bottom of the casing to the ejector providing a space between said means and the ejector to receive the latter, 70 the ejector being in position to eject the outermost blade through said space clear of said means.
